CLAIM

The ornamental design for a portion of a display panel with a graphical user interface, as shown and described.

DESCRIPTION

FIG. 1 is a front view of a first image in a sequence of a portion of a display panel with a graphical user interface; and,

FIG. 2 is a second image thereof.

The appearance of the transitional image sequentially transitions between the images shown in FIGS. 1-2. The process or period in which one image transitions to another image forms no part of the claimed design.

1 Claim, 2 Drawing Sheets
